UNITED STATES PATENT OFFICE.

FRANCIS ROURK, OF ERIE, PENNSYLVANIA.

APPARATUS FOR OPERATING VELOCIPEDES AND OTHER MACHINES.

Specification forming part of Letters Patent No. **90,310**, dated May 18, 1869.

To all whom it may concern:

Be it known that I, FRANCIS ROURK, M. D., of Erie, in the county of Erie and State of Pennsylvania, have invented a new and Improved Apparatus for Operating Velocipedes and other Machines; and I do hereby declare the following to be a full and exact description of the same, reference being had to the accompanying drawings, which form a part of this specification, and the letters of reference marked thereon.

The nature of my invention consists in such a combination of levers and cranks in such a position as to enable a man to operate them with ease and in such a manner as to greatly increase his weight on the said levers and cranks, and also to greatly increase his natural force. The said power may be applied to a variety of purposes. In the accompanying drawings I have applied it to the propelling of a velocipede. It may with equal ease be applied to the propelling of a shaft from which any kind of machinery may be operated by any desired mode of communicating power and motion.

In the accompanying drawings, Figure 1 is a perspective view, and Fig. 2 is a top view, of my machine as applied to the propelling of a velocipede.

In the drawings can be seen the shaft or axle E, with its five cranks, D', D', C', C', and A', the levers D, D, C, C, and A, together with the connecting-rods D², D², C², C², and A².

The manner in which I construct one of my machines is as follows: I first construct a main shaft or axle, E, with the five cranks D', D', C', C', and A', as shown in the drawings. To each of these cranks I attach connecting-rods or pitmen as follows: To the cranks D' and D', I attach the connecting-rods D² and D², which connect the levers D and D. To the cranks C' and C', I attach the connecting-rods C² and C², which connect with the levers C and C at the

seat B, and to the crank A', I attach the connecting-rod A², which connects with the lever A, which has its fulcrum on the cross-bar K. The levers D, D, C, and C have their fulcrums at their extremities farthest from the axle or shaft E—as, for example, at the points G and H. The levers C and C are connected at their extremities nearest to the axle E by a cross-bar, B, which serves as a seat for the operator, and to the under side of which the pitmen C² and C² are attached by means of staples, thereby giving play-room for the oscillating motion of the said pitmen.

The manner in which my machine is operated is as follows: The operator seats himself on the seat B and places his feet in the stirrups I I on the levers D D, and then grasps the lever A with his hand. He then (supposing the machine to stand as indicated in Fig. 1) pushes the lever A from him, bearing his whole weight on the seat B, continuing to do so till it reaches its lowest point. He then transfers his weight to the levers D and D by standing on his feet, and draws the lever A toward him. This causes a complete revolution of the shaft, and of course the operation is so continued.

It will be noticed the operator is, by means of the action described, constantly increasing his own weight, and by the arrangement of the levers as described he is also increasing his natural force, making the power of the machine many times more than that of a man.

I claim—

The shaft E, the cranks D', D', C', C', and A', the connecting-rods D², D², C², C², and A², and the levers D, D, C, C, and A, or their equivalents, when arranged and operated substantially as described, and for the purposes set forth.

FRANCIS ROURK, M. D.
